SAFETY DEVICE FOR VOLATILE LIQUID STORAGE TANKS

John J. Tokheim, Cedar Rapids, Iowa

Original application January 25, 1937, Serial No. 122,278. Divided and this application November 15, 1937, Serial No. 174,726

3 Claims. (CL. 220—89)

This invention relates to a safety device for volatile liquid storage tanks and is a division of my application, Serial No. 122,278, filed January 25, 1937.

Storage tanks for gasoline and the like must be provided with adequate venting means not only to take care of the expansion of air or vapor above the fluid level therein, but also to permit the ingress of air when the liquid fuel is withdrawn from the tank to prevent the formation of a vacuum which would tend to collapse the tank. Moreover, such vents must be so constructed as to provide adequate protection against fire, dust, sand, rain, snow and ice. In that connection the invention contemplates a structure including suitable valves housed within a flame arrester or cage which permits of free access to the atmosphere so that the valves may reliably function under normal conditions of use, and, on the other hand, will be amply protected in the case of fire to prevent failure of the valves and also to prevent ignition of the contents of the tank.

A special object of the invention is to provide a novel weather shield which in normal use adequately protects the valves from water or snow and ice, and which, in case of fire, will drop out of position to compel flame propagation on the outside of the cage.

A further object of the invention is to provide a novel type of fusible unit for connecting the weather shield to the frame work of the flame arrester.

With the above and other objects in view which will more readily appear as the nature of the invention is better understood, the same consists in the novel construction, combination and arrangements of parts hereinafter more fully described, illustrated and claimed.

A preferred and practical embodiment of the invention is shown in the accompanying drawing, in which:

Figure 1 is a vertical sectional view illustrating the invention.

Figure 2 is a top plan view, partly in section of the construction shown in Figure 1.

Figure 3 is a detail perspective view of a portion of the weather shield and cover showing the fusible link connecting the same.

Figure 4 is a detail perspective view of one of the flame arresting plates.

Similar references designate corresponding parts throughout the several figures of the drawing.

According to the embodiment of the invention

shown in the drawing, the same includes in its organization a vapor condensation compelling and pressure relief or blow off valve A surrounded by an annular series of vacuum valves B, all housed within a valve cage designated generally as C and including a flame arrester surrounded by a weather-shield D.

The cage C comprises a base 1 having a central internally threaded nipple 2 for mounting the entire device on a vent pipe P connected with the storage tank in the usual manner. The base 1 is provided at its outer periphery with a plurality of posts 3 which may be secured thereto by suitable fastenings 4. These posts are channeled or grooved at opposite sides to form guideways for receiving the opposite ends of the metal flame arresting plates 6. These plates are provided with integral offset spacing projections so that when they are arranged in stacked formation in the opposed channels 5 of adjacent posts, they provide intervening air passages for establishing communication between the valves A and B and the atmosphere. The plates in each stack may be conveniently held together by the fastenings 8. The top of the posts 3 support a cover plate 9 which is preferably secured to the posts by the fastenings 10 having winged heads to facilitate their placing and removal.

The outer edge of the cover plate 9 is preferably flanged downwardly as indicated at 11 to provide an annular recess for receiving the upper end of the frusto-conical weather shield D. The body of the shield is provided with a plurality of slots or openings 12 formed by striking out an ear 13. This ear is perforated to receive the shank of an eye-bolt 14 said shank being tensioned by a coil spring contained within a housing 15. The eye 14 receives a fusible link or loop 16 which engages the fastening 17 on flange 11. This arrangement locates the fusible link 16 at the hole or slot 12, and the spring tensioned eyebolt 14 holds the weather-shield D firmly in place. In the event of fire, any flame propagated at the outer side of the plates 6 will pass through the openings 12 and quickly melt the links 16 thereby permitting the shield to drop. Ordinarily, however, the shield remains in the position shown in Figure 1 to prevent water entering the valve cage, or to prevent the formation of ice on the plates which would obstruct the free passage of air. The cover 9 is provided with a central boss 18 which is interiorly threaded to receive a tubular valve stem guide 19. The upper end of the tubular guide is fitted with a removable cap 20. As will be observed from the drawing, the guide 18

19 receives the stem 20' of the pressure relief valve A to guide it in its movement.

The foraminous valve cage, dust and sand screen flame arrester and its weather shield are essential to the proper functioning of all of the valves and the means which permits the shield to drop; in case of fire affords further protection to the tank as the flame will blaze outwardly and upwardly, in place of being forced down against the tank roof. Since the flame arrester and valve cage prevent fire propagation to the valve chamber, but burns entirely on the outside of plate stack 6. The valves function properly under fire and when the vapor pressure on the tank becomes less than the valve pressure, the valve closes and automatically the fire is extinguished for lack of fuel.

Without further description it is thought that the features and advantages of the invention will be readily apparent to those skilled in the art, and it will, of course, be understood that changes in the form, proportion and minor details of construction may be resorted to, without departing from the spirit of the invention and scope of the 25 appended claims.

I claim:

1. In a safety device for volatile liquid storage

tanks, a flame arrester, a cover for the flame arrester, a weather shield in the form of a frustoconical member having its upper edge normally engaged with the cover, a plurality of fusible members carried by the cover, and spring means carried by the weather shield and engaging said members to connect the weather shield to the cover under tension.

2. In a safety device for volatile liquid storage tanks, a flame arrester, a cover for the flame arrester, a weather shield in the form of a frustoconical member having its upper edge normally engaged with the cover, studs carried by the cover, fusible links suspended from said studs, and yielding means carried by the weather shield 15 for engaging said links.

3. In a safety device for volatile liquid storage tanks, a flame arrester including a side wall having lateral openings, a cover on the upper side of the flame arrester, an annular weather-shield 20 suspended from the cover by fusible links for shielding the side wall of the flame arrester, said weather-shield having flame escape openings at the location of the fusible links.
